SHEET-COLLATING.

1,314,776.

Specification of Letters Patent. Patented Sept. 2, 1919.

Original application filed January 4, 1917, Serial No. 140,512. Divided and this application filed December 29, 1917. Serial No. 209,420.

To all whom it may concern:

Be it known that I, LESTER A. WERNERY, a citizen of the United States, residing in Brooklyn borough, in the county of Kings, 5 city and State of New York, have invented certain new and useful Improvements in Sheet-Collating, of which the following is a specification.

This invention relates to manifolding, and 10 more particularly to work-sheets for use in collating purposes in a typewriting machine.

This application is a division of my pending application, Serial No. 140,512, filed January 4, 1917 (now Patent No. 1,275,637, 15 dated August 13, 1918.)

Usually, at the end of the month, after a statement-sheet and ledger-sheet have been made out, the statement is delivered to the customer, and the ledger-sheet is stored in 20 a loose-leaf binder. When it is desired to write the statement for the following month, a new statement-sheet is so collated with the same ledger-sheet, that the first entry to be made will follow the last line written upon 25 said ledger-sheet. This is done so that the ledger-sheet shall form a compact record of all transactions. It will be noted, therefore, that the typing relation between the statement and ledger-sheets is to vary after the 30 statement-sheet for each month has been written, and that the amount of variation is determined by the number of lines that have been written upon the previous statement.

The sheets of the present invention are 35 collated by means of shoulders provided at the sides of the sheets for coöperation with alining or positioning devices provided upon the typewriting machine. These shoulders aline the sheets with respect to the machine 40 and also with respect to one another, so that the lines of writing upon each sheet register with the lines of writing upon the other sheets.

In order that the ledger-sheet may be 45 properly collated with the statement-sheet (and with the usual duplicate or copy of the statement-sheet), the present invention provides a detachable border on each side of the ledger-sheet, consisting of a series of detachable segments or tabs, formed by lines of perforations at intervals corresponding to the blank writing lines upon the sheet. 50 These detachable segments may, therefore, be in the form of integral extensions or

margins of the ledger-sheet, but separated 55 from the body of the ledger-sheet by a longitudinal row of perforations, and separated from one another by transverse rows of perforations which extend from the longitudinal row of perforations to the outside 60 edge of the sheet. Evidently the same results may be obtained by scoring the paper or by any means which will render the work-sheet less resistant to separation along such lines of division. These segments may be 65 torn from the ledger-sheet either one by one or in a group. The number of segments removed after a statement has been completed, corresponds with the number of lines that have been typed upon the statement-sheet. 70 It will thus be seen that the proper number of segments having been removed, the ledger-sheet is in condition to properly locate itself in respect to the next statement-sheet, by means of the shoulders which are 75 left where the last segments were torn off. The detachable segments upon one side of the sheet match those upon the other side, and this enables the sheet to aline itself when the shoulders on both sides are 80 brought against the alining pins in the typewriter.

These sheets are preferably used with a typewriting machine, but may also be used upon any device which serves as a support 85 for work-sheets for manifolding; or these work-sheets may be collated by means of stop-pins outside of the machine, then clipped together, and finally inserted in the typewriting machine. 90

Other features and advantages will hereinafter appear.

In the accompanying drawings,

Figure 1 is a perspective view, showing the manner in which the work-sheets are collated. 95

Fig. 2 shows the statement-sheet.

Fig. 3 is a fragment of a duplicate statement-sheet showing the detachable segments.

Fig. 4 is a fragment of the ledger-sheet. 100

A ledger-sheet 10, a sheet 11 to become a duplicate statement, and the statement-sheet 12 itself, with intervening carbon sheets 13, may be fed around a platen 14 of the typewriting machine to printing position by the 105 usual paper-feeding mechanism.

In order that the sheets may be easily and quickly collated to proper typing positions,

each is provided at each side with a shoul-
dered portion 14^a to engage a stop-pin 15,
so that the proper lines to be written upon
on each sheet will register with one another
5 and all in register with the printing point
of the typewriter.

In practice, the separate transactions are
written at intervals during the month, the
ledger-sheet being collated with the state-
10 ment-sheets so that the entries will be sim-
ultaneously made on all the sheets.

To enable the ledger and statement-sheets
to be self-locating, even though the relative
printing relation between the sheets varies
15 from time to time, the ledger-sheet is pro-
vided at its side margins with a plurality of
detachable segments 16. These are formed
by vertical perforations 17 made near the
side margins of the sheet, and horizontal per-
20 forations 18 which lead from the vertical
perforations to the edge 19; the horizontal
perforations 18 corresponding in their spacing
with the lines of writing on the ledger-
sheet. Usually the ledger-sheet is ruled, and
25 these horizontal perforations may coincide
with the ruled lines.

When it is desired to collate a new state-
ment with the ledger-sheet, the detachable
segments 16 on the ledger-sheet are torn
30 along the lines of the perforations 17 and 18,
until a series of segments which correspond
in number to the number of lines written
upon on the previous statement-sheet have
been removed. For instance, if six lines
35 have been written upon on the previous state-
ment-sheet, six detachable segments are re-
moved from the ledger-sheet before the new
statement-sheet is collated therewith.

After the ledger-sheet has been located
40 with the shoulders formed by the first un-
removed segments 16 against the collating
pins 15, the duplicate statement-sheet 11 may
be advanced until arrested by a shoulder or
shoulders 20 thereon. The main state-
45 ment-sheet 12 may then be advanced until located
by its shoulders 21 at the side margins 22 en-
gaging with the collating pins 15. The
shoulders 21 are so positioned upon the state-
ment-sheet that the first blank line of the
50 statement-sheet is now in writing position.

The side margin 22 may, if desired, be sep-
arated from the main portion of the state-
ment-sheet by a line of perforations 23, so
that after typing the sheet, the margin 22
55 may be removed.

The duplicate statement-sheet 11 may be
similar to the statement-sheet 12, but need
have no heading, and therefore need not be
provided with a shoulder at a distance from
60 the top edge of the sheet. The upper corners
of the sheet may serve for collating.

In the preferred form, the first detachable
segment 24 of the ledger-sheet is made of
considerable length, because of the depth of
65 the usual heading on the ledger-sheet; that

is, the shoulder formed by detaching the top
segment will serve to position the ledger-
sheet by engaging with the stop-pins 15, with
the first blank line on the ledger sheet in
register with the printing point of the type- 70
writing machine.

The short sheet 25, shown in Fig. 3, may
be provided in case it is desired to keep a
duplicate of the ledger-sheet. This sheet
has the detachable segments 16 throughout 75
its side margin. It is not necessary to pro-
vide the large segment 24 for this duplicate,
because it need not have an extensive head-
ing.

The ledger-sheet 10 and the duplicate state- 80
ment 11 may be provided, adjacent their
side margins, with perforations 26 for bind-
ing.

After the sheets have been collated, the
pins may be moved to ineffective position, 85
or the sheets may be moved away from said
pins and advanced.

It will be seen that the sheets are not only
self-locating relatively to one another, but
also as to their positions with reference to 90
the printing point 27 of the typewriter; the
shoulders and pins being arranged on oppo-
site sides of the sheets. Hence, after the
sheets are placed in the machine and ad-
vanced to engage with the collating pins, it 95
is unnecessary to further adjust the sheets
with relation to one another or with relation
to the printing point.

Variations may be resorted to within the
scope of the invention, and portions of the 100
improvements may be used without others.

Having thus described my invention I
claim:

1. A self-locating work-sheet for use in
a typewriting machine or the like, having 105
gages to coöperate with the edge portions of
said sheet, said sheet having its side edges
formed with detachable border portions, the
connections between the body portion and
said border portions being such as to permit 110
the latter to be readily pulled away from
the former, each detachable border portion
consisting of a row of individually detach-
able segments, the segments of the border
115 portions being symmetrical with respect to
the body portion of said work-sheet.

2. A work-sheet for use in a typewriting
machine having gages to coöperate with the
side portions of said sheet to determine an 120
initial position of the same, comprising op-
posite side edge portions having provisions
whereby tearing along the side edges will
tend to take place along lines extending gen-
erally in parallelism to said side edges and
125 along lines, at line-space intervals, extend-
ing from said first-mentioned lines to the
corresponding edges.

3. A work-sheet for use in typewriting
machines having gages to coöperate with the
edge portions of said sheet to determine the 130

initial position of the same, comprising side border portions integral with the body of said sheet but separated therefrom by lines along which the material has been weakened, so that tearing of said sheet will tend to follow certain lines, said border portions being separated into segments by lines along which said sheet has been weakened, said last-mentioned lines being at line-space distances apart and extending from the edges of said work-sheet to said first-mentioned lines.

4. A work-sheet adapted for use in a machine having normally fixed gage members, comprising portions to be brought into engagement with said gage members, said engaging portions being integral with the body of said work-sheet, but separated therefrom by lines along which the material has been weakened.

20 5. A self-locating work-sheet having detachable borders formed by a longitudinal row of perforations at each of its side margins, and a plurality of transverse lines of perforations extending from each of the 25 longitudinal rows of perforations to the corresponding outside edge of the sheet and dividing said borders into segments, said transverse lines of perforations being arranged at line-space intervals on the sheet, 30 the removal of certain of said segments rendering the next succeeding segment effective as a shoulder for engagement with fixed gage members, the position of said shoulders determining the position of the sheet, thus 35 rendering it self-locating.

6. In combination, a set of work-sheets for simultaneous use in a typewriting machine or the like, said set of work-sheets comprising a sheet having a single positioning 40 shoulder thereon at each side margin, and another sheet having a plurality of detachable segments at each of its side margins to provide shoulders, the shoulders on the first-mentioned sheet and the shoulders 45 formed by selected segments on the second-mentioned sheet being so placed on the respective sheets that, when the two sets of shoulders are brought into register and alinement with one another, the desired lines 50 of writing upon these sheets will be caused to register and aline with one another.

7. A work-sheet adapted for use in a recording machine having gage members, comprising edge portions adapted to coöperate 55 with said gage members to properly position said work-sheet, said edge portions being integral with said work-sheet but separated therefrom by lines along which the material has been weakened to facilitate the removal 60 of said edge portions.

8. A work-sheet adapted for use in a type-writing machine having gage members, comprising side edge portions, each presenting at a suitable distance from the head of the 65 work-sheet a shoulder to coöperate with the

corresponding gage member, said edge portions being separated from the body of said work-sheet by lines along which the resistance against separation is less than in adjoining portions of said work-sheet, to facilitate the removal of said edge portions. 70

9. A work-sheet for use in a typewriting machine having positioning members to co-operate with said sheet to determine the position thereof, comprising side border portions integral with the body portion of said work-sheet but separated therefrom by lines of weaker material, lines of weaker material extending across said border portions at line-space intervals forming segments, certain of said segments being removed when required, so that the work-sheet, when placed in the machine in coöperation with said positioning members, will be positioned in accordance with its own shape. 75 80

10. A work-sheet for use in typewriting machines having positioning members to co-operate with said sheet to determine the position thereof, comprising a body portion of less width than the distance between said 90 positioning members, and border portions providing means to coöperate with said positioning members, the connection between the body of the sheet and each of said border portions being of less strength than the material on each side of said connection, whereby said border portions may readily be pulled away from said body portion when no longer required. 95

11. A work-sheet for use in machines having positioning members to coöperate with said sheet in determining the position thereof, comprising a body portion of less width than the distance between said positioning members, and side border portions providing means to coöperate with said positioning members, the connection between the body of the sheet and each of said border portions being of less strength than the material on each side of said connection, each 100 border portion being made up of sections of line-space height, the connections between said sections being of less strength than the material of which said sections is composed, whereby any desired number of said sections 105 110 may readily be pulled away from the remainder of the work-sheet to obtain the configuration required to effect proper positioning of said work-sheet, and whereby all of said border portions may be removed when 115 no longer required. 120

12. In combination, a set of collated work-sheets for simultaneous use in a type-writing machine, comprising a sheet having side border portions, each of which is provided 125 with a single positioning shoulder, the connection between said border portions and the body portion of said sheet being of less strength than the adjoining portions of said sheet, to permit pulling apart of said side 130

- 4
- border portions and said body portion, and a second work-sheet of the same width as the first, comprising a body portion and side border portions, the connection between each 5 of said border portions and said body portion being of less strength than the adjoining portions of said sheet, said border portions of the second sheet being composed of sections of line-space height, having connections 10 thereof between of less strength than that of the adjoining portions, the collation of said two sheets being effected by bringing into alignment the shoulders on the first sheet and shoulders on the second sheet 15 presented by any of said sections exposed by the removal of preceding sections.
13. In combination, a set of collated work-sheets for simultaneous use in a typewriting machine, comprising a sheet having a body portion and side border portions, each 20 of said border portions being provided with a shoulder, and a second sheet comprising a body portion and side border portions, each of said border portions of said second sheet 25 being composed of sections of line-space height, the connections between the border portions and the body portions of the first and second sheets, and the connections between the sections and the border portions 30 of the second sheet being of less strength than the adjoining portions of said sheets.
14. A work-sheet for use in a typewriting machine having positioning members to co-operate with said sheet in determining the 35 position thereof, comprising a body portion of less width than the distance between said positioning members, and side border portions, each of said side border portions being composed of a series of sections, certain
- of which are of line-space height, said sections being symmetrically arranged on opposite sides of said body portion, the connections between said body portion and said border portions and between the sections of said border portions being of less strength 45 than the adjoining portions of said work-sheet, to permit ready separation along said connections.
15. A work-sheet for use in a typewriting machine having positioning members to co-operate with said sheet in determining the 50 position thereof, comprising a body portion of less width than the distance between said positioning members, and a side border portion composed of a series of sections, certain 55 of which are of line-space height, the connections between said body portion and said border portion and between the sections of said border portion being of less strength than the adjoining portions of said work-sheet, to permit ready separation along said connections.
16. A work-sheet comprising a body portion and means to assist in positioning said body portion for use, including border portions composed of segments, said segments being symmetrically arranged with reference to said body portion, and the connections between the body portion and the border portions and between the segments of 70 the border portions being such that the segments may readily be pulled apart and may readily be pulled away from the body portion.

LESTER A. WERNERY.
